Patented Mar. 21, 1922.

2 SHEETS—SHEET 2.

UNITED STATES PATENT OFFICE.

JOSEPH J. LEGG, OF LUMBERTON, MISSISSIPPI.

CAR DOOR.

1,409,957.

Specification of Letters Patent. Patented Mar. 21, 1922.

Application filed April 2, 1921. Serial No. 457,867.

To all whom it may concern:

Be it known that I, JOSEPH J. LEGG, a citizen of the United States, residing at Lumberton, in the county of Lamar and 5 State of Mississippi, have invented certain new and useful Improvements in Car Doors, of which the following is a specification.

This invention relates to car doors, and it comprises a track arranged above the door 10 opening, an upper door section having brackets secured thereto, rollers carried by said brackets and engaging said track, a lower section provided with a longitudinal groove on its lower edge, a plate secured to the 15 floor and entering said groove, and locking means for said door, said means comprising an angle iron carried by each of said sections adjacent one side of the door, an angle iron pivotally mounted in the doorway and 20 adapted to engage said angle irons to prevent movement of the door, and an arm carried by said pivoted angle iron and adapted to be fastened to the door.

In the present invention, I have provided 25 an improved type of sliding door for cars wherein the door is made in two sections, the upper section being adapted to slide over the lower section and be mounted on a track arranged above the doorway. An interlocking 30 tongue and groove construction is provided at the meeting edges of the two sections to prevent the upper section from becoming displaced. The door sill is provided with an upwardly extending plate adapted 35 to enter a longitudinal groove in the lower section to retain the lower section of the door in place. Means are provided for readily and quickly locking and sealing the door, comprising a pin or rod projecting from one 40 of said sections and adapted to pass through an opening in a pivoted arm carried by the other section. The two sections of the door are thus maintained locked to each other, and when the upper section is to be opened, 45 the hinged arm is disengaged from said pin to permit movement thereof. The two sections are retained in closed position by means of flanged plates projecting from the outside of the door and adapted to be engaged 50 by a hinge or pivoted plate mounted on the door casing. This plate is provided with an arm extending over said rod or pin, and having an opening for the reception of said rod or pin. When the door is in closed position, and the two arms are arranged over 55 said rod, a lock or seal is arranged in an

opening in the end of the rod to prevent unlawful manipulation of the doors of the car.

In the accompanying drawings, I have shown one embodiment of the invention. In 60 this showing:

Figure 1 is a side elevation of the door in closed position,

Figure 2 is a transverse vertical sectional view on line 2—2 of Figure 1, 65

Figure 3 is a similar view of a portion of the door on a slightly enlarged scale,

Figure 4 is a similar view of the upper section of the door on a slightly enlarged scale, 70

Figure 5 is a horizontal sectional view on line 5—5 of Figure 1,

Figure 6 is a similar view on line 6—6 of Figure 1,

Figure 7 is a detail perspective view of 75 the upper door section,

Figure 8 is a similar view of the lower section,

Figure 9 is a detail view of the locking member, and, 80

Figure 10 is a similar view of a lock or seal.

Referring to the drawings, the reference numeral 1 designates an ordinary type of freight car which is provided with a roof 2, 85 and a floor 3. The side of the car is provided with an opening or doorway 4, and a track 5 is arranged over the doorway and extended into a housing 6, for the reception of the door when in open position. The 90 floor of the car is provided with the usual sill 7, having an upwardly extending flange or guide 8, which is also extended into the housing 6 (see Figure 5).

The door comprises a lower section 9, and 95 an upper section 10. As shown, the lower section is provided with a longitudinal groove 11 on its lower edge, for the reception of the upwardly extending plate or rib 8. The upper edge of the lower section of 100 the door is cut away at each side to provide a projecting tongue 12. A pair of plates 13 are secured to the lower edge of the upper section forming a groove for the reception of tongue 12, to retain the two sections of 105 the door in proper vertical alinement. A plurality of brackets 14 are secured to the upper edge of the upper door section, the brackets extending upwardly beyond the upper edge of the upper door section and being 110 provided with a substantially inverted U-shaped portion 15. Rollers 15 are journaled

in the arms of the inverted U-shaped portion of the bracket, and these rollers are adapted to ride on the track 5 and support the door. As shown, the rollers are provided with grooves 17 to prevent them from becoming displaced from the track.

The upper section of the door is locked to the lower section by means of a hinged arm 18, secured thereto at any suitable point and adapted to normally lie in a recess 19 in the face of the upper door section so that the arm, when in closed position, will lie flush with the surface of the door (see Figure 2). The lower door section is provided with a groove or recess 20, through which the lower end of arm 18 extends when the two sections of the door are in closed position. A locking pin 21 is arranged on the lower door section and this pin is adapted to pass through an opening 22 on the end of the arm 18 when the doors are in alignment with each other. As shown, the lower end of the arm is offset, as at 23, to permit the locking elements to be arranged substantially flush with the surface of the door. The lower door section is provided with a horizontal groove or recess 24, for the reception of the offset end of the hinged arm which permits the arm to be arranged substantially flush with the face of the door when in unlocked position with the sections of the door out of alignment with each other.

Each of the door sections is provided with an outwardly extending flange 25, adjacent its outer end. When the door is in closed position, these flanges are adapted to be arranged beside the side wall 26 of the door frame. A locking member 27 is pivotally mounted in the doorway, the locking member being provided with ears 28 for the reception of pivot pins. As shown, the locking member is formed of angle iron, and comprises a pair of arms 29 and 30, the arm 29 being arranged transversely of the car and abutting the flanges 25 when in closed position (see Figure 6), and the arm 30 being arranged along the outer face of the door. The arm 30 is provided with an extension 31, having an offset end 32, which is adapted to enter the groove 24. The offset end is provided with an opening 33, for the reception of the locking pin 21.

When the door is in the position shown in Figures 1 to 3 of the drawings, the hinged arm 18 is arranged over the locking pin to retain the two door sections in vertical alignment, and the offset end 32 of the extension 31 is then arranged over the locking pin. Any suitable type of locking means may be arranged in an opening 34, arranged in the locking pin to retain the arms 31 and 18 on

the pin. A seal 35 may be attached to a chain 36, carried by the extension 31, and passed through the opening 34, as shown in Figures 2 and 3. After the seal has been placed in position, it may be closed and the car sealed.

When the car is to be opened, the seal or other locking means is first removed, and the locking member 27 turned at right angles to the position shown. It will be apparent that the flange 25 will then be free to move, permitting the door to be opened. If merely the upper section of the door is to be opened, the arm 18 is removed from the end of the locking pin to permit independent movement of the upper section of the door.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A car door comprising upper and lower sections slidably mounted in the side of a car, an arm hinged to one of said sections and extending over the other section, said arm being provided with an opening adjacent its free end, a locking pin carried by said second section and adapted to be received in said opening, said door sections being provided with outwardly extending flanges adjacent one end, an angle iron hinged to the car, one arm of said angle iron being adapted to engage said flanges, when in closed position, the other arm thereof being arranged substantially parallel to the face of the door, and an extension arranged on said second arm, said extension being provided with an opening adjacent its free end and being adapted to receive said locking pin.

2. A car door of the character set forth in claim 1, wherein said door sections are provided with substantially vertical grooves adapted to align with each other when the door is closed, said first mentioned arm being adapted to be arranged in said grooves, and wherein the lower door section is provided with a horizontal groove adapted to receive the extension formed on said second arm.

In testimony whereof I affix my signature in presence of two witnesses.

JOSEPH J. LEGG.
